DESIGN FOR PRINTING FLOOR-CLOTHS.

James Albro Jr Carpet Pattern No 14
Patented Dec 20 1843

UNITED STATES PATENT OFFICE.

JAMES ALBRO, JR., OF ELIZABETHTOWN, NEW JERSEY.

DESIGN FOR PRINTING FLOOR-CLOTHS.

Specification forming part of Design No. 14, dated December 20, 1843.

To all whom it may concern:

Be it known that I, JAMES ALBRO, Jr., of Elizabethtown, in the county of Essex and State of New Jersey, have invented and produced a new and original Design for the Printing of Floor Oil-Cloths; and I do hereby declare that the accompanying drawings are full and exact representations of the same, which I claim as my invention and desire to secure by Letters Patent, not confining myself to the size or colors of the accompanying drawings.

To enable others skilled in the art to make and use my design, I will state that the way in which I print it is with blocks cut into pegs measuring eight to the inch.

JAMES ALBRO, JR.
